UNITED STATES PATENT OFFICE.

CHARLES A. CREAPO, OF ST. PAUL, MINNESOTA.

REFRIGERATOR.

1,354,536.

Specification of Letters Patent.

Patented Oct. 5, 1920.

Application filed March 21, 1919. Serial No. 284,145.

To all whom it may concern:

Be it known that I, CHARLES A. CREAPO, a citizen of the United States, residing at St. Paul, in the county of Ramsey and State of Minnesota, have invented a new and useful Refrigerator, of which the following is a specification.

My invention relates to refrigerators, and the object is to provide a refrigerator in which no ice or ammonia is required to produce the chill required in domestic and other ordinary refrigerators.

In the accompanying drawing, Figure 1 is a top view of my improved refrigerator. Fig. 2 is a front elevation of Fig. 1. Fig. 3 is an enlarged section on the line 3—3 in Fig. 2. Fig. 4 is a vertical section of the refrigerator on the line 4—4 in Fig. 3. Fig. 5 is a vertical section on the line 5—5 in Fig. 3.

Referring to the drawing by reference numerals and showing the invention as embodied in a small refrigerator or "ice-box" used in or near the family kitchen for keeping milk, meats, butter and other groceries cold during the warm season of the year, 6 designates a casing having either legs or a downward rim 7 forming a hollow base 8, in which is disposed the usual dripping pan 9, 20 having a tube 10 for leading water into the sewer piping of the building.

The top 11, bottom 12, back 13, sides 14 and front 15, the latter with door 16, are all formed with double air spaces 17, 18, which 35 are separated by a thick paper or cardboard partition 19, secured on strips 20, which have air holes 20* and are secured to either the inner shell 22 or the outer shell 21. Said shells are preferably made out of thin 40 sheet metal and are lined at their adjacent sides with thick paper 23. The door 16 is hinged at 24 and provided with suitable locking means 25.

Placed within the casing 6 is a slightly 45 smaller skeleton frame having a front opening 26 (shown in dotted line in Fig. 3) facing the opening for the door 16. Said skeleton frame is formed of flat tubes 27, communicating with vertical corner tubes 50 28. One of said corner tubes has its upper end connected to a water supply 29 of the water works system in the building in which

the refrigerator is placed, and the corner post diagonally therefrom has its lower end provided with a water outlet pipe 30, provided with a drip valve 31 outside the box 6 so it can be seen and regulated; it is arranged to drip water into a chute or pipe 32, which extends into the base 8 and leads into the dripping pan 9.

In Fig. 4 is indicated how by means of hooks 33 shelves, like 34, may be suspended from the horizontal tubes 27 in the sides of the refrigerator. It is also evident that shelves may be supported on said tubes without the use of the hooks 33, by simply making the shelves long enough to extend with their ends partly upon the tubes.

In the operation or use of the refrigerator a valve 35 (shown in Fig. 2) is opened until 70 the whole tubular structure 27—28 is filled with cold water, the valve is then turned almost shut, so that only a dripping or slight flowing will take place from the valve 31. The latter valve will also aid in regulating 75 the flow of the water according to requirement, as the atmospheric temperature may vary. In all towns and cities having a regular water works the same is placed so deep in the ground that the water gets cold 80 enough to keep the temperature in the refrigerator amply cold to prevent spoiling of groceries and other things placed therein.

In houses or hotels where a hot water system is maintained for supplying hot 85 water to bath rooms and faucets in general, one of my devices may be installed and connected with the hot water pipes, and used for keeping cooked food warm until it is to be placed on the table. The inner frame 90 will in that event serve as a heat radiator, while in the refrigerator it serves as an absorber of the heat in the refrigerating space.

The air spaces 17, 18, and lining 23 and the intermediate wall or partition 19 all 95 help to prevent the cold air from absorbing heat through the walls, top or bottom of the inclosure 6.

As for the cost of operation, actual demonstration proves that in ordinary cities 100 and towns where water from the water-works can be had at the rate of one-fourth to one-sixth of a cent per barrel, and ice costs about half a cent per pound, it is a great

saving of money to use my improved refrigerator instead of the kind cooled with ice.

What I claim is:—

A refrigerator comprising a casing, a skeleton frame within said casing composed of horizontally extending flattened tubes having their major diameters arranged in

vertical planes, and communicating with vertical corner tubes, said frame being provided with a fluid supply inlet and a fluid outlet having means for regulating the flow of the fluid through the frame.

In testimony whereof I affix my signature.

CHARLES A. CREAPO.
